SPANNER WRENCH HEAD OR SIMILAR ARTICLE

Lucian W. Gaskins, 4425 Sandy Lane Road,
Columbus, Ohio

Filed Oct. 25, 1963, Ser. No. 77,158

Term of patent 14 years

(Cl. D54—16)

FIG. 1 is a perspective view of a spanner wrench head or similar article showing my new design;

FIG. 2 is a top plan view;

FIG. 3 is an end elevational view;

FIG. 4 is a side elevational view; and

FIG. 5 is a bottom plan view thereof.

I claim:

The ornamental design for a spanner wrench head or similar article, substantially as shown.
